SIGNALING DEVICE

Adolf J. Haltrich and William J. Haltrich,
Cleveland, OhioApplication March 9, 1932, Serial No. 597,746
In Canada February 12, 1932

7 Claims. (Cl. 177—339)

This invention relates to a signaling device, and more particularly to a device of the character by which the driver of a vehicle can signal his intention of making a turn, to the traffic behind 5 him.

An object of the invention is to provide an improved signal which may be manually actuated by the driver, and which will be automatically discontinued after a predetermined period of time. 10 Another object is to provide an improved signaling device which will be simple in construction and operation.

Another object is to provide an improved signaling device which will effectively attract the 15 attention of an observer.

Other objects will hereinafter appear.

The invention will be better understood from the description of one practical embodiment thereof illustrated in the accompanying drawing, in which:

Figure 1 is a plan view of the switch mechanism used for operating the signal lights, the covering therefor being removed.

Figure 2 is a longitudinal section taken on the 25 line II—II of Figure 1.

Figures 3 and 4 are fragmentary views similar to Figure 1, but showing positions of the parts in operation.

Figure 5 is a wiring diagram.

This application is, in part, a continuation of 30 our prior application Serial Number 441,656, filed April 4, 1930.

It has heretofore been proposed to provide the rear of an automobile or like vehicle with lights 35 for indicating that the driver is about to make either a right or left turn.

These signals have in general been manually actuated, being turned on by the driver before 40 making the turn, and turned off thereafter. Due to the distractions of modern traffic, the driver is inclined to forget to turn off these lights after having made a turn, and the drivers following him are thereby confused and the signal fails to accomplish its purpose. Due to the number of 45 lights carried by vehicles, such as the tail-lights, stop lights, and the like, a signal for indicating turns should force itself upon the attention of an observer and differentiate itself from other signal lights to prevent confusion with them.

By the applicants' invention, the driver may 50 turn on the signal lights, which will remain on for a sufficient period of time to permit him to make the contemplated turn, and will then be automatically turned off.

The signal may also be operated so that it

will not be confused with the usual tail-light or stop signal, this being effected by causing the light to be illuminated and darkened alternately, which not only distinguishes the signal from those mentioned, but in addition attracts the eye of an observer and so assists in making certain that he will see the signal. 5

In Figure 5, two signal lights 1 and 2 are shown for indicating, respectively, left and right turns, these each consisting of an electric bulb in a reflecting casing covered by an appropriate lens which may bear any desired indicia, shown as arrows, in the drawing, the lights most conveniently being positioned adjacent the usual tail-light or rear license number of the vehicle 10 on suitable supports (not shown), or at the sides and rear of the vehicle, as by being mounted upon the fenders. 15

The lights are connected by conductors 3 and 4 with the switching mechanism indicated in this figure generally by 5, and are grounded as indicated at 6 and 7. The switching mechanism is in turn connected by a conductor 8 to the battery 9 of the vehicle, which itself is grounded as indicated at 10. It will be apparent that 20 when the circuit is completed through conductor 3, electricity is furnished to light 1, and when the circuit through conductor 4 is closed the electricity is furnished to light 2. 25

The switching mechanism consists of an insulated base 11 which may be attached by a clamp 12 to the steering column of the vehicle immediately below the steering wheel. Upon this base is pivoted an operating lever 13 carried by a post 14 and having its inner end formed into a flattened vertical bearing section 15 provided with a depending lug 16 which engages a slot in a movable contacting finger 17. A second finger 18 is secured to and in electrical contact 30 with the first. 35

Two continuous stationary arcuate contacts 19 and 20 are carried by the base 11 and positioned so that upon movement of the lever, contacting finger 17 will be drawn along one or the other of them. The conductors 3 and 4 are connected to the contacts 19 and 20 respectively. 40 45

A conductor 21 is positioned along the lower surface of the base 11 and has a plurality of projections 22 formed upon it which project through the insulating material of the base and are arranged to be contacted by finger 18 when the lever is moved to one side or the other. The conductor 21 is connected by means of a wire or the like 23 to a binding post 24 with which 50 conductor 8 is connected. Mounted upon the 55

binding post 24 is a contact 25 arranged beneath a lamp socket 26 formed in the base 11 and a second contact 27 is also supported beneath this socket and connected directly to the post 14.

- 5 It will therefore be seen that when the end of the lever 13 is moved to the right the parts assume the position shown in Figure 4, in which finger 17 is bearing upon contact 20 and finger 18 passes from one to another of the contacts 10 22.

Current flows through conductor 8 to the binding post 24 at which point it may divide, part passing through lamp 28 mounted in the socket 26 thence through contact 27 to post 14, through finger 17, to contact 20 and thence through conductor 4 to light 2. When the current follows this path only, as when finger 18 is between two successive contacts 22, the resistance of the two lamps 28 and 2, being in series, limits the amount 20 of current so that the lamp 2 is not visibly illuminated, while lamp 28 is illuminated. When finger 18, however, touches one of the points 22, the current can pass directly from binding post 24 through wire 23, conductor 21, contact 22, fingers 25 18 and 17 to contact 20 and thence directly through conductor 4 to lamp 2. When this condition obtains, sufficient current is supplied to lamp 2 to brilliantly illuminate it. Therefore, as the lever is moved, lamps 28 and 2 are alternately illuminated as the current alternately is caused to flow through lamp 28 or permitted to circumnavigate this lamp and pass directly to lamp 2. Similarly, if the lever is moved to the left as shown in Figure 3, the lamp 1 will be alternately illuminated, its illuminations also alternating with those of lamp 28.

Pivoted upon posts 29 carried by the base 11 are two oppositely disposed bell-crank-like levers 30 and 31 having curved ends which bear upon 40 the sides of end 15 of the lever. The opposite ends of these levers are arranged to engage a head 32 connected to a piston 33 which reciprocates in cylinder 34 carried by the base 11. Within the cylinder and surrounding the stem 45 35 of the piston is a compression spring 36 which bears at its inner end upon the piston and at its outer end upon a cap 37 secured to the cylinder. This spring is arranged to return the lever to its central position in which fingers 17 and 18 are out of contact with contacts 19, 50 20 and 22.

The closed end of cylinder 34 is provided with a threaded aperture in which is inserted a slotted screw 38, a piece of rubber tubing or the like 55 39 and spring 40 being used to surround the screw and prevent the same from becoming loose, as well as to restrict escape of air from the cylinder. The size of the discharge opening may be regulated by adjusting the screw to vary the 60 area of the slot which extends beyond the end of the cylinder.

A vent is provided through cap 37 so that when the piston shank is drawn out by either 65 of the levers, no compression of air between the cap and piston is caused. The cylinder may also be provided with a vent about half way of its length, which will be uncovered by the piston when drawn outwardly to allow air to enter the closed end of the cylinder.

70 Obviously, when the lever is moved to actuate one of the lights, the spring will tend to restore the parts to their normal positions, but this restoration will be delayed by the action of piston 75 in expelling the air from the cylinder, and the

time taken to expel this air will be proportional to the area of the vent provided by screw 38.

A spring washer 41 and fiber washer 41a are used to clamp the lever to post 14, a coil spring 42 also being provided to prevent looseness of the parts. The clamping of the lever between the washers acts as a brake to prevent the lever from being returned by vibration or the like until it is moved by the action of the spring, piston and bell-crank levers.

10 Top and bottom covers 43 and 44 are provided to enclose the switch parts and may be clamped together by screws passing through the covers as well as the insulating base 11.

15 The levers 13 may be downwardly offset, so that it passes out through a slot in the lower part of the casing, preventing the entrance of rain or the like to the switch mechanism.

20 While we have described the illustrated embodiment of our invention in some particularity, obviously many others will readily occur to those skilled in the art to which this appertains, and we therefore do not limit ourselves to the precise details shown and described herein, but claim as our invention all embodiments, variations and modifications coming within the scope of the subjoined claims.

25 We claim:

1. A signal including a switch comprising a pivoted lever, two contacting fingers movable therewith and electrically connected together, elongated spaced stationary contacts in the path of one of said fingers arranged to be selectively engaged thereby, an elongated series of spaced contacts 30 electrically connected together in the path of the other of said fingers and arranged to be successively contacted thereby, a source of electrical energy connected to said series of contacts, a resistance element interposed between said source of energy and said contacting fingers, and two signal lights one connected to each of said first 35 mentioned contacts.

2. A signal including a switch comprising a pivoted lever, two contacting fingers movable therewith and electrically connected together, elongated spaced stationary contacts in the path of one of said fingers arranged to be selectively engaged thereby, an elongated series of spaced contacts 40 electrically connected together in the path of the other of said fingers and arranged to be successively contacted thereby and of substantially the same extent as both said first mentioned stationary contacts, a source of electrical energy connected to said series of contacting fingers, a resistance element interposed between said source of energy and said contacting fingers, and two signal lights one connected to each of said first 45 mentioned contacts.

3. A signal including a switch comprising a pivoted lever, two contacting fingers movable therewith and electrically connected together, elongated arcuate spaced stationary contacts in the path of one of said fingers arranged to be selectively engaged thereby, an elongated series of 50 spaced contacts electrically connected together and arranged concentric with said pivot in the path of the other of said fingers to be successively contacted thereby and of substantially the same angular extent as both said first mentioned stationary contacts, a source of electrical energy connected to said series of contacts, a resistance element interposed between said source of energy and said contacting fingers, and two signal lights 55

- one connected to each of said first mentioned contacts.
4. A signal including a switch comprising a pivoted lever, two contacting fingers movable therewith and electrically connected together, elongated spaced stationary contacts in the path of one of said fingers arranged to be selectively engaged thereby, an elongated series of spaced contacts electrically connected together in the path of the other of said fingers and arranged to be successively contacted thereby, a source of electrical energy connected to said series of contacts, a resistance element interposed between said source of energy and said contacting fingers, two signal lights one connected to each of said first mentioned contacts, and resilient means returning said fingers to a position where the first finger is out of contact with said first mentioned contacts, and means controlling the return to said position.
5. A signal including a switch comprising a pivoted lever, two contacting fingers movable therewith and electrically connected together, elongated spaced stationary contacts in the path of one of said fingers arranged to be selectively engaged thereby, an elongated series of spaced contacts electrically connected together in the path of the other of said fingers and arranged to be successively contacted thereby, a source of electrical energy connected to said series of contacts, a resistance element interposed between said source of energy and said contacting fingers, two signal lights one connected to each of said first mentioned contacts, resilient means returning said fingers to a position where the first finger is out of contact with said first mentioned contacts, means controlling the return to said position, and braking means resisting the motion of said lever
- and cooperating with said first mentioned controlling means to control the return of the fingers.
6. Signaling apparatus adapted to actuate a signal light and a pilot light comprising a manually movable switch member, resilient means for returning said switch member to its normal position, means controlling the return of said member, a circuit arranged to be closed when said member is moved from normal position, and including both said lights in series, a circuit shunted around the pilot light and including said signal light, and a series of circuit closing means in said last mentioned circuit successively operated by the motion of said member.
7. Signaling apparatus adapted to actuate either of two signal lights and a pilot light, comprising a manually movable switch member, resilient means for returning the switch member to its normal position, means controlling the return of said member, two circuits each including one signal light and having a common portion including the pilot light, one of said circuits arranged to be closed when the switch member is moved from normal position in one direction and the other arranged to be closed when the switch member is moved from normal position in another direction, and either circuit when closed including its signal light and the pilot light in series, two circuits shunted around the pilot light one connected to each of the first mentioned circuits, and including the signal light of said circuit, and a series of circuit closing means in said last mentioned circuits successively operated by the motion of said member.
